PORTABLE RAILWAY TRACK GRINDER

Henry H. Talboys, Milwaukee, Wis., assignor to
 Nordberg Manufacturing Co., Milwaukee, Wis.,
 a corporation of Wisconsin

Application December 10, 1934, Serial No. 756,779

10 Claims. (Cl. 51—178)

This invention relates to an improvement in portable railway track grinders and especially to the type as is universally portable both on and off railway track. The form illustrated here is of particular use along railway tracks under repairs. One object is to provide a track working tool which can be rolled along the rails of a track or pushed along the ground. Another object is the arrangement of supporting brackets for carrying tools ahead of a barrow wheel and thereby counterbalancing the machine. Another object is to maintain the power unit on a pivot to permit of more readily leading the flexible drive shaft in any direction. Another object is to provide an extension on one side of the machine to support it approximately in an upright position when either on or off the track. Another object is to provide a sleeve for the extension support, so that it can be telescoped into the sleeve to counterbalance the machine while being wheeled along the ground. Another object is to provide a belt tightener and means to relieve all belt tension during starting of the power unit. Other objects will appear from time to time in the course of the specification and claims.

I illustrate my invention more or less diagrammatically in the accompanying drawings, wherein—

Figure 1 is a plan view of the machine having a grinding tool at one end of the flexible shaft;

Figure 2 is an elevation of the machine on a railway track;

Figure 3 is a sectional view and detail of the driving pulley with an overload release and means for attachment of the flexible shaft, section being made on the line 3—3 of Figures 1 and 4.

Figure 4 is a section on the line 4—4 of Figure 2, showing an end view of the power unit with belt tightener and pivotal arrangement.

Like parts are indicated by like symbols throughout the specification and drawings.

Referring to the drawings, I generally indicates the frame of a portable railway track grinder made up of two frame members having horizontal portions 2, which are bowed inward and upward at 3 and meet a common cross-member 4, to which they are welded. The opposite ends of the frame 1—2, are bent to form handles 5. Lugs 26 welded on the frame 1—2 provide a support for the shafts of the double conical track wheels 27, these shafts having sleeves slipped over them to abut against said lugs 26 and the wheels 27 to align them in the middle of the frame 1—2. A cross member is

welded at 6 to stiffen the frame and support the tool box 7 and at 3 a tubular cross member 3a strengthens the frame and forms a telescope into which fits an extension arm 8 held in position by a removable pin or pins 9 in apertures 9a—9a which, upon withdrawal, will permit the extension arm 8 to be withdrawn entirely or reversed or telescoped inward so as to balance the frame structure. A pin opening at 10 permits of locking the extension arm in its inward position when 10 matched with either of the holes 9a. The opposite end of the extension arm is provided with a roller 11, of known construction, which registers with one rail of the track and may be insulated from the rest of the machine to permit its being 15 pushed over live track without interference with the signaling system.

The tool box 7 has two lugs welded to the top of it numbered 67 which, together with lugs 14, form a means for carrying the flexible shaft when 20 not in use.

At 12 there are two lugs welded to the frame 1 which form the support for a pneumatic barrow wheel 13, which is a standard product available on the market. The shaft of this barrow wheel 25 is bolted to the lugs 12 in a substantial but usual manner, so that as the frame handles 5 are lifted, and the barrow wheel is depressed, part of the weight will be carried thereon. Ample clearance is provided around the wheel, so that it may 30 not be jammed by slight misalignment.

Clips 14 welded to the frame 1 are so spaced that the flexible shaft, to be described later, may fit therebetween for easier transportation, and both such clips are drilled with a hole 15 for a 35 pin, so that when the flexible shaft is in place between the clips, the pin may be dropped into holes 15 to secure the flexible shaft.

On the cross-member 4, there are welded two brackets 16 bent hook-shaped below to carry the 40 necessary grinding tool when conveyed to a work location. These brackets are located well forward beyond the shaft of the barrow wheel 13 and with the grinding or any other tool in place thereon tend to counterbalance the weight of 45 the power unit.

In the center of the frame 1, the plate 17 (Figures 2 and 4) is welded on to act as a stiffener for the frame and as a platform for supporting the power unit 18. Drilled opening 19 in this 50 plate provides a pivotal bearing for a king pin 20, which is rigidly attached to a foundation plate 21 by welding or otherwise. Below the plate 17 and surrounding the king pin 20, there is a washer 22 which is prevented from falling off by a pin 55

23 located in place in the well-known manner and penetrating a hole at right angles to the axis of the king pin 20. A plate washer 24 is located between the platform plate 17 and the foundation plate 21 to permit of more readily turning the foundation plate 21 and the power unit 18 bolted thereto. The power unit 18 is attached to the foundation plate 21 by means of bolts 25. The king pin 20 with the pin 23, the foundation plate 21 with bolts 25, and the power unit 18 thereby become a unit assembly pivotally mounted on the washer plate 24 and prevented from upsetting by the king pin 20, washer 22 and pin 23.

Welded to one end of the foundation plate 21 are two lugs 28 set in an upright position and having holes 29 drilled through them to take a shaft 30 which forms a pivot for two vertical bars 31 to the upper ends of which is welded a pipe 32, being slotted at the top as at 33. The inside diameter of this pipe is small enough to form a clamping fit for the sleeve 34 which forms a holder for the bearing for the shaft of the driven pulley 35.

The two uprights 31 with the tubular cross-members 32 form a bracket to support the driven pulley 35. The lower end of this bracket, and around the shaft 30, has another tube 32a welded to both vertical members 31, so as to form a substantially rectangular unit. Welded to this lower tube is a laterally extending arm 36 which forms a rigid unit with this bracket. At a point farthest away from the pivotal shaft 30 a pin is welded as part of the extension 36 to which is attached one end of a spiral spring 37. The upper end of this spring is in hook form and hooks into the links of a chain 38. A clip 39 is provided, either welded or bolted to the frame of the power unit 18, which forms a rigid foundation for it and which is provided with a slot 40, the openings of this slot being just large enough to permit a link of the chain to enter flatwise. By means of this arrangement, it is possible to increase or decrease the tension of the spring 37 by merely hooking any respective links of the chain 38 into the slot 40 to suit the tension required.

The power unit 18 is provided with a driving pulley 42 which is in alignment with the driven pulley 35, a belt 43 being stretched between the pulleys. The tension of this belt is controlled by a pressure tending to separate the two pulleys, which is brought about by means of a bracket 31, the extension 36 and the spring 37.

By entirely disconnecting the chain from the clip 39 and slot 40, the belt tightener can be thrown toward the power unit, thereby loosening the belt so that starting of the unit is facilitated. This arrangement is necessary to make starting of the engine reliable and easy, and brings about smoother starting of the flexible shaft. Such power units are generally started by hand. The crank for the starting of the engine illustrated is shown at 41.

The pulley 35 in Figure 3, with bushing 44 pressed tightly therein, runs loosely on the outside of the driving shaft 45. A ring 46 fitted on the inside of pulley 35 forms a ball seat for an overload release, generally shown as 47. This release may have two or more such balls 50, each one fitted into a slight indentation under it, this indentation matching and opposed to one in the opposite ring marked 48. The ring 48 is keyed to shaft 45, so as to drive it positively. A ball retainer ring 49 is centered on the shaft 45 and has two or more drilled openings of a diameter 75 slightly greater than that of the balls to keep

them centrally and in alignment with the opposed indentations, in case the balls are displaced outside of said indentations provided for them in rings 46 and 48.

With this arrangement so far described, it will be seen that the pulley 35 can move laterally and thereby cause the balls to roll out of their respective indentations, and rotate easily for a fraction of a revolution without driving the shaft 45. The ring 46 is keyed to the pulley 35 by means of pins 51 to prevent its turning. It will be seen that if the pulley 35 is pressed toward the ring 48 at a time when the balls have slipped into the indentations provided for them, the shaft 45 can be driven as long as such pressure endures and provided the torque on shaft 45 is not too great. In order to provide a means for exerting such pressure, the end of the shaft 45 is extended to form a thread extension 52 having a nut 53 fitted over it, and a washer under same marked 54. A spring 55 is compressed between the washer 54 and the pulley 35. It will be seen that by changing the compression of spring 55 by means of the nut 53, varying degrees of pressure may be exerted upon the balls and thereby a varying degree of torque may be transmitted from the pulley 35 to the shaft 45. It will also be noted that this will form a reliable overload release arrangement which, when the torque on the shaft 45 becomes too great, will cause the balls to be rolled out of the indentations provided for them and will rotate far enough until they are seated in the next succeeding indentation in the direction of rotation. The pulley thereby is caused to move slightly in a lateral direction every time the balls slip into and out of the indentations provided for them. The nut 53 is provided with a locking arrangement in the form of a setscrew or the like marked 56, which fits into a slot in the threaded extension 52 and permits of an adjustment of the spring and the locking of the nut at each half revolution thereof.

The shaft 45 extends into a sleeve housing 34 in which are mounted a plurality of ball bearings. At each end of the sleeve 34 are one or more sets of these ball bearings acting as a radial bearing 45 as well as a thrust bearing to react against the tendency to jar the shaft 45 laterally out of its fixed position when the overload release is thrown into or out of engagement.

The ball bearing 57 forms a united thrust and 50 radial bearing for shaft 45 and the ball bearing 58 forms merely a bearing. The bearing 51 is held in place by means of a threaded screw plug 59 meshing with the thread in the sleeve 34, plug 59 being arranged with a means for locking it in place. The opposite end of the sleeve is threaded as at 60 to receive a socket 61, provided with a locking mechanism 62 which holds one end of a flexible shaft 63. The rotating member of the flexible shaft extends inward in the socket 61, as at 64, by means of the usual driving arrangement, as at 65, and transmits the motion of the shaft 45 to the shaft 64.

The flexible shaft and its connecting units are part of a device readily available on the market 65 and need not be described further, as these do not form part of this invention.

The opposite end of the flexible shaft may be attached to any form of grinding tool. The particular tool shown generally as 66 in the present 70 instance is the cup wheel grinding attachment in which the grinding wheel is adjustable in a vertical direction. As this does not form part of the present invention, it is not further described.

It will be seen from the foregoing that the 75

present machine is a general utility power plant which may ride on the rails of a track or may be wheeled from one track to another or along a site on which a track is later to be located. Any 5 tool requiring rotary motion may be attached to the end of the flexible shaft, such as grinders, bits, low powered wrenches, etc. The engine being pivotally connected to the frame of the machine permits the use of a short and inexpensive 10 flexible shaft, inasmuch as the power unit will turn to suit the direction in which the power is to be led. Furthermore, by avoiding bends and twists of the flexible shaft, its life is considerably enhanced. The power unit may be turned on 15 the frame of the machine in such a direction as will facilitate the laying of the flexible shaft on it without bending the shaft excessively.

Space is provided on this machine for carrying 20 of such small tools as are most generally needed by the operator. The power unit may be turned on the frame in such a direction that the starting handle for the engine may be in the most convenient position.

When the extension arm 8 is telescoped into 25 the sleeve 3, it will form a support for the machine when off the track. It may be extended on either side as the occasion demands. When conveying the machine long distances, it is considered easier to push it on a track than on the ground, so that the combination of the barrow wheel with the railway wheels will make this 30 machine very popular for work along railway track.

In case this tool is used on a live track, it can 35 readily be wheeled off to permit the passing of a train and is readily put back again after the train has passed.

I claim:

1. In a tool of the class described, a frame 40 adapted to ride on the rail of a track, a plurality of track engaging flanged rollers longitudinally spaced along said frame, and an unflanged wheel mounted upon said frame and normally aligned with and overlying the rail 45 on which the flanged rollers ride, the lowest portion of said wheel being positioned above the level of the rail when both the flanged rollers engage the rail, and handle means associated with said frame, whereby said frame may be 50 tilted to bring said wheel into contact with a supporting surface, said frame being provided at one end with an upwardly extending handle portion and at the other with an upwardly extending portion to which said wheel is pivoted, 55 the axes of said wheel and said flanged rollers being parallel.

2. In a tool of the class described, a frame, a supporting wheel for said frame, said frame including a forward portion upon which said wheel 60 is mounted, handle means for said frame, whereby it may be employed as a barrow, a power plant on said frame, a flexible shaft associated with said power plant, an operating tool adapted to be operated by said flexible shaft and flexible 65 therewith, and mounted on the end thereof, and supporting means upon said frame, forward of said wheel, for supporting said tool and shaft, when they are out of use, with said tool positioned on the opposite side of the axis of 70 rotation of the wheel from the power plant.

3. In a tool of the class described, a frame, means for supporting said frame upon one rail of a track, tool actuating means on said frame, and a tool adapted to be actuated by said means, 75 and a telescoping extension from said frame to

the opposite rail of said track, including one telescopic member fixed in relation to said frame, and a second telescopic member penetrating the first telescopic member and slidable in relation thereto, sufficiently to permit said second member to extend in part to the opposite side of the frame from that on which it is normally positioned, and a rail engaging means associated with the outer end of said second telescopic member. 10

4. In a tool of the class described, a frame, means for supporting said frame upon one rail of a track, tool actuating means on said frame, and a tool adapted to be actuated by said means, and a telescoping extension from said frame to 15 the opposite rail of said track, including one telescopic member fixed in relation to said frame, and a second telescopic member penetrating the first telescopic member and slidable in relation thereto, and a rail engaging means associated 20 with the outer end of said second telescopic member, and means for securing said second telescopic member in extended position and in retracted position with the opposite ends of said telescopic members substantially in balance. 25

5. In a track working tool, a frame including a central portion adapted to be aligned over one rail of a track, flanged rollers rotatably mounted upon said central portion, a wheel support projecting upwardly from the forward end of said 30 central portion, a barrow wheel rotatably mounted on said upwardly projecting portion, said barrow wheel lying in the vertical plane of the rail engaged by said flanged rollers, and a handle portion extending upwardly from the end of the 35 frame opposite to the barrow wheel the axes of said barrow wheel and said flanged rollers being parallel.

6. In a track working tool, a frame including a central portion adapted to be aligned over one rail of a track, flanged rollers rotatably mounted upon said central portion, a wheel support projecting upwardly from the forward end of said central portion, a barrow wheel rotatably mounted on said upwardly projecting portion, said barrow wheel lying in the vertical plane of the rail engaged by said flanged rollers, and a handle portion extending upwardly from the end of the frame opposite to the barrow wheel the axes of 45 said barrow wheel and said flanged rollers being parallel, said barrow wheel, when the flanged rollers are engaged with the rail, being out of contact with the rail. 50

7. In a track working tool, a frame, means for 55 supporting said frame upon one rail of a track, including a pair of flanged rollers longitudinally spaced along said rail, a platform on said frame, mounted intermediate said rollers, a handle extending upwardly from one end of said frame, an 60 extension upwardly from the opposite end of said frame, and a single barrow wheel rotatably mounted on said extension, the diameter of said barrow wheel substantially exceeding the diameter of the flanged rollers, the axes of rotation of 65 the flanged rollers and the barrow wheel being parallel, the barrow wheel and the rollers being longitudinally aligned in the vertical plane of the rail upon which the flanged rollers ride.

8. In a track working tool, a frame, means for 70 supporting said frame upon one rail of a track, including a pair of flanged rollers longitudinally spaced along said rail, a platform on said frame, mounted intermediate said rollers, a handle extending upwardly from one end of said frame, an 75

extension upwardly from the opposite end of said frame, and a single barrow wheel rotatably mounted on said extension, the diameter of said barrow wheel substantially exceeding the diameter of the flanged rollers, the axes of rotation of the flanged rollers and the barrow wheel being parallel, the barrow wheel and the rollers being longitudinally aligned in the vertical plane of the rail upon which the flanged rollers ride, the lowest portion of said barrow wheel, when the flanged rollers are in supporting contact with the rail, being spaced slightly upwardly from the surface of the rail.

9. In a track working tool, a frame, means for supporting said frame upon one rail of a track, including a pair of flanged rollers longitudinally spaced along said rail, a platform on said frame, mounted intermediate said rollers, a handle extending upwardly from one end of said frame, an extension upwardly from the opposite end of said frame, and a single barrow wheel rotatably mounted on said extension, the diameter of said barrow wheel substantially exceeding the diameter of the flanged rollers, the axes of rotation of the flanged rollers and the barrow wheel being parallel, the barrow wheel and the rollers being longitudinally aligned in the vertical plane of the rail upon which the flanged rollers ride, a power plant mounted upon said platform, for free rotation, in relation to said frame, about a generally vertical

axis, a flexible transmission extending from said power plant, a tool mounted upon said flexible transmission and flexible freely therewith, and a support for said tool mounted upon the barrow wheel supporting extension of the frame. 5

10. In a track working tool, a frame, means for supporting said frame upon one rail of a track, including a pair of flanged rollers longitudinally spaced along said rail, a platform on said frame, mounted intermediate said rollers, a handle extending upwardly from one end of said frame, an extension upwardly from the opposite end of said frame, and a single barrow wheel rotatably mounted on said extension, the diameter of said barrow wheel substantially exceeding the diameter of the flanged rollers, the axes of rotation of the flanged rollers and the barrow wheel being parallel, the barrow wheel and the rollers being longitudinally aligned in the vertical plane of the rail upon which the flanged rollers ride, a power plant mounted upon said platform, for rotation, in relation to said frame, about a generally vertical axis, a flexible transmission extending from said power plant, a tool mounted upon said flexible transmission and flexible freely therewith, and a support for said tool mounted upon the barrow wheel supporting extension of the frame at a point outwardly beyond said barrow wheel. 10 15 20 25

HENRY H. TALBOYS. 30
